[57] CLAIM

The ornamental design for combined plush animal handbag set, as shown and described.

DESCRIPTION

FIG. 1 is a front perspective of a combined plush animal handbag showing my new design;

FIG. 2 is a side elevational view of the embodiment of FIG. 1;

FIG. 3 is a rear elevational view of the embodiment of FIG. 1;

FIG. 4 is a top plan view of the embodiment of FIG. 1;

FIG. 5 is a bottom plan view of the embodiment of FIG. 1;

FIG. 6 is a front perspective view of a combined plush animal handbag set showing my new design in a panda bear embodiment;

FIG. 7 is a side elevational view of the embodiment of FIG. 6;

FIG. 8 is a rear elevational view of the embodiment of FIG. 6;

FIG. 9 is a top plan view of the embodiment of FIG. 6;

FIG. 10 is a bottom plan view of the embodiment of FIG. 6;

FIG. 11 is a front perspective view of the larger animal in the embodiment of FIG. 1; and,

FIG. 12 is a rear perspective view of the smaller animal in the embodiment of FIG. 1.

FIG. 11

FIG. 12
